UNITED STATES PATENT OFFICE

GUSTOV C. SHAFFER, OF CHICAGO, ILLINOIS.

DUMPING FREIGHT-CAR.

1,093,734.

Specification of Letters Patent.

Patented Apr. 21, 1914.

Application filed July 11, 1913. Serial No. 778,465.

To all whom it may concern:

Be it known that I, GUSTOV C. SHAFFER, a citizen of the United States, and a resident of the city of Chicago, county of Cook, and 5 State of Illinois, have invented certain new and useful Improvements in Dumping Freight-Cars, of which the following is a specification.

My invention relates to dumping freight 10 cars and more specifically to that class thereof generally known as "gondola" freight cars.

The object of my invention is the production of a car of the character mentioned 15 which will be durable and economical of construction, and in which will be provided doors for the discharge openings of the car of improved construction and operation.

Other objects will appear hereinafter.

20 The invention consists in the combinations and arrangements of parts hereinafter described and claimed.

The invention will be best understood by reference to the accompanying drawings 25 forming a part of this specification, and in which—

Figure 1 is a side elevation of a freight car embodying my invention, Fig. 2 is an enlarged end elevation of the lower portion 30 of the body of the car, Fig. 3 is a vertical transverse section through the body of the car, and Fig. 4 is a detail section taken on substantially line $x-x$ of Fig. 3.

The preferred form of construction as 35 illustrated in the drawings comprises a car body formed of sheet metal, said body consisting of side walls 1, end walls 2 and a bottom 3. Said bottom 3 is inclined from a longitudinal median line toward the sides 40 of the car so that, in use, when the doors of the discharge openings 1' of the car are moved to open positions, the contents of the car will automatically discharge through said openings as will be readily understood.

45 The lateral walls 1 of the car body are reinforced at intervals by vertically disposed flanges 4 spaced along said walls as clearly shown in Fig. 1, the discharge openings 1' of the car being positioned between said reinforcing flanges as shown in the several views. Secured to the flanges 4 at opposite sides thereof are angle irons 5 between the outwardly projecting adjacent flanges of which are constituted channels 6. Coöperating 50 with each of the discharge openings 1' is a metallic door 7 which is mounted for

vertical sliding, the respective ends thereof being mounted in the corresponding guide channels 6 as clearly shown in Fig. 4.

The arrangement is such as will be observed that the doors 7 will normally remain at their lower terminals of movement or in closed position, the same assuming this position, by reason of gravity. Elevation of said doors in order to effect dumping 60 of the car is secured through racks 8 secured to the outer side of each of said doors adjacent the respective ends thereof as clearly shown in Fig. 4. The racks 8 are engaged by pinions 10 secured to shafts 9 which extend longitudinally of the car in front of said doors, said shafts being mounted in bearings provided in the flanges 4. Four shafts 10 are employed, two on each side of the car, each extending from the 65 center of the car to one end thereof. The arrangement is such, as will be observed, that elevation of the doors 7 may be effected by rotating said shafts. Said shafts are manually rotated through the medium of a 70 lever 11 which is provided at the outer end of each of said shafts, said lever carrying a pawl 12 which is adapted to engage with a ratchet wheel 13 provided at the corresponding end of the shafts, a spring compressed pawl 14 coöperating with said ratchet wheel to lock the same in advanced 75 position during oscillation of lever 11, as will be readily understood. With this arrangement it will be seen that, when it is 80 desired to release the doors from elevated position, it is only necessary to move the pawls 12 and 14 to inoperative positions, the doors after said pawls have been thus moved dropping by gravity to closing 85 position.

Provided at the lower edge of each of the doors 7 adjacent the respective extremities thereof are rollers 15 which engage with the corresponding angle members 5 to alleviate friction in the sliding movement of the doors it being obvious that when the car is laden, there will be considerable outward pressure upon the doors 7, and which pressure would result in considerable friction of said doors upon the outermost angle members 5 but for the provision of the rollers 15.

The doors 7 as well as the shafts 9 and pinions 10 are positioned inwardly of the 110 sides of the car, the lateral walls 1 of the latter being offset, as clearly shown in Fig.

3, in order to accommodate said doors in this arrangement. By offsetting the walls 1 as shown, housings are constituted thereby for the reception of the doors 7 when in 5 elevated position. This construction will be found to be especially strong and durable and the same affords protection for the doors 7 and the operating mechanism thereof of which will prevent injury thereto such as 10 might otherwise result were said doors exposed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations 15 and modifications as come within the scope 20 of the appended claim.

Having described my invention what I claim as new and desire to secure by Letters Patent is:

A freight car comprising a side wall having a discharge opening, said opening having vertical guide grooves at the ends thereof; a door coöperating with said opening having its ends mounted for vertical sliding in said guide grooves, said door being positioned inwardly of the corresponding side of the car, said wall being offset to accommodate said door; and means for effecting vertical movement of said door, substantially as described. 25 30 35

In testimony whereof I have signed my name to this specification in the presence of two subscribing witnesses.

GUSTOV C. SHAFFER.
